[57] CLAIM

The ornamental design for a game board, as shown and described.

DESCRIPTION

FIG. 1 is an enlarged perspective view of a game board, showing my new design;

FIG. 2 is a top plan view thereof;

FIG. 3 is a bottom plan view thereof;

FIG. 4 is a one side elevational view thereof, the three other side views being mirror images thereof;

FIG. 5 is a top plan view thereof with the right side of each extension folded under the left side of each respective extension;

FIG. 6 is a bottom plan view thereof with right side of each extension folded under the left side of each respective extension;

FIG. 7 is one side elevational view thereof with the right side of each extension folded under the left side of each respective extension, the three other side views being mirror images thereof; and,

FIG. 8 is an enlarged perspective view thereof, completely folded.

FIG. 1

FIG. 2

FIG. 3

FIG. 4

FIG. 5

FIG. 8

FIG. 6

FIG. 7
